KARL STRECKERT, OF KARLSRUHE-GRUNWINKEL, GERMANY

HYDRAULIC CHANGE-SPEED GEARING

Application filed June 28, 1928, Serial No. 288,895, and in Germany June 29, 1927.

My invention relates to improvements in hydraulic change speed gearings, and more particularly in gearings of the type comprising a rotary pump and a rotary motor operating 5 atively connected with each other and enclosed in a revolving casing, the drum of the pump being connected with the driving shaft and the casing with the driven shaft, means being further provided for controlling the 10 flow of the motive fluid from the pump to the motor so that either the said flow is interrupted and both shafts are directly coupled with each other, or the fluid flows from the pump to the motor for transmitting the 15 power at the desired ratio.

One of the objects of the improvements is to provide automatic means for controlling the flow of the motive fluid so that the gear ratio can be continuously varied within 20 broad limits, and with this object in view my invention consists in constructing the rotary motor so that its working chamber is varied in accordance with the resistance opposed to the driven shaft, by varying the eccentricity 25 of the casing of the motor and its drum. For directly coupling the driving shaft and the driven shaft without making use of the transmission of power by the motive fluid the casing of the motor is set concentrically of 30 the drum, so that the active working chamber is zero, while the casing of the motor is set more and more into eccentric position in the degree as the pressure of the motive fluid is increased, so that an increasing volume of 35 motive fluid flows through the system resulting in an increasing difference of the velocities of the driving and driven shafts. The construction is such that the motive fluid flowing through the motor causes an additional 40 moment of the driven shaft, which moment is added to the moment transmitted thereto by the coupling action of the system, so that the resultant moment of force acting 45 on the driven shaft is increased as compared to the moment of the driving shaft.

For the purpose of explaining the invention two examples embodying the same have been shown in the accompanying drawings in 50 which the same reference characters have

been used in all the views to indicate corresponding parts. In said drawings,

Fig. 1 is a sectional elevation showing the improved change speed gearing,

Figs. 2 and 3 are sectional elevations taken 55 on the lines 2—2 and 3—3 of Fig. 1 and looking in the direction of the arrows,

Fig. 4 is a detail sectional view taken on line 4—4 of Fig. 1 and showing the mechanism locking the drum of the motor against 60 rotation in one direction, and

Figs. 5 and 6 are sectional elevations similar to those shown in Figs. 2 and 3 and showing a modification.

In the example shown in Figs. 1 to 4, my 65 improved change speed gearing comprises a cylindrical casing *g* having the driving shaft *a*¹ concentrically mounted therein, the said shaft being supported with both ends in the heads of the casing *g*. The casing *g* is rigidly connected with the driven shaft *b*, and it is filled with a suitable motive fluid such as oil. Near the inner end a drum *t*¹ is fixed to or made integral with the driving shaft *a*¹, which drum is provided with radially movable vanes *k*¹, and the drum and vanes are rotatable within a casing *l*¹ disposed within the casing *g*. In its heads the casing *l*¹ is provided with intake openings *o*¹ communicating with the inner part of the casing *g*, and in its cylindrical wall it is provided with an opening *d*¹ communicating with a pipe *d* disposed longitudinally of the casing *g*. The pipe *d* is closed at its left hand end, and it is passed through a cylindrical bore *l'* of 70 the casing *l*¹ thus providing a bearing for the said casing *l*¹ permitting rocking movement thereof within a plane transverse of the driving shaft *a*¹.

At its right hand end the pipe *d* is fixed to or made integral with the left hand head of a casing *l*² disposed within the casing *g*, the opposite head of the said casing being provided with a trunnion *e* disposed coaxially of the pipe *d* and rockingly mounted in a bore of the right hand head of the casing *g*. Thus, the casing *l*² is likewise capable of rocking movement about the axis of the pipe *d*. The casing *l*² is formed with a passage *d*² 80 in alignment and communicating with the 85 90 95 100

pipe d and further opening into the casing l^2 . Further, the casing l^2 is provided with an opening o^2 opening into the casing g .

Within the casing l^2 there is a drum t^2 provided with radially movable vanes k^2 , the said drum being fixed to or made integral with a hollow shaft a^2 concentrically mounted on the driving shaft a^1 and projecting through the right hand head of the casing g . To the outer end of the said hollow shaft a disk Z is fixed on which spring-pressed pawls z are rockingly mounted which are adapted for engagement with ratchet teeth p provided on a frame P of the apparatus, the said pawl and ratchet teeth permitting rotation of the drum t^2 only in the direction of the rotation of the shaft a^1 .

The casing l^1 is acted upon by a leaf spring f^1 fixed with one end to the inner face of the casing g and loosely engaging with its opposite end a nose g^1 projecting inwardly from the cylindrical wall of said casing. The median part of the spring bears on a lug m^1 projecting outwardly from the cylindrical wall of the casing l^1 . Diametrically opposite to the pipe d providing the pivot of the casing l^1 , the said casing is formed with a transverse cylinder C^1 having a plunger c^1 mounted therein, which plunger bears on a bolt x^1 fixed to the left hand head of the casing g . The cylinder C^1 communicates through a passage v^1 made in the cylindrical wall of the casing l^1 with the pressure chamber D provided within the pipe d , so that the plunger c^1 is always acted upon by the fluid pressure within the chamber D . The power of the spring f^1 is such that it holds the casing l^1 in the position shown in Fig. 2 and eccentric to the drum t^1 , as long as the fluid pressure within the chamber D is below a certain value, the eccentricity of the casing being determined by the bolt x^1 engaged by the plunger c^1 . The casing l^2 is acted upon by a leaf spring f^2 fixed with one end to the cylindrical wall of the casing g and loosely engaging with its opposite end a lug g^2 projecting inwardly from the cylindrical wall of the said casing, the median part of the said spring bearing on a lug m^2 projecting outwardly from the cylindrical wall of the casing l^2 . Diametrically opposite to the pipe d the casing l^2 is formed with a transverse cylinder C^2 containing a plunger c^2 bearing on an abutment x^2 fixed to the right hand head of the casing g . The cylinder C^2 communicates with the pipe d through a pipe v^2 . Lugs r and y engaging each other and provided respectively on the cylindrical walls of the casings g and l^2 hold the casing l^2 acted upon by the spring f^2 in the position concentric to the drum t^2 , as is shown in Fig. 3. But in lieu of the said abutments r and y the plunger c^2 can be made to bear on the bottom of the cylinder C^2 thus providing the

stop for holding the casing l^2 in the concentric position.

The strength of the springs f^1 and f^2 is not the same, but it is such that the casing l^2 is displaced by a lower pressure of the motive fluid than the casing l^1 .

At the top part of the casing l^1 there is a safety valve i .

The operation of the gearing is as follows:

If the parts are in the positions shown in the figures, and the driving shaft a^1 is rotated in the direction of the arrows shown in Figs. 2 and 3, the drum t^1 tends to take liquid from the casing g through the intake openings o^1 and to force the same through the opening d^1 into the pressure chamber D . Since the drum t^2 is in symmetric position within the casing l^2 , the said casing is not capable to receive the liquid. Therefore the said liquid is arrested within the chamber D , and it prevents rotation of the drum t^1 relatively to the casing l^1 , so that the said casing and the casing g take part in the rotary movement of the driving shaft, and the driven shaft b rotates at the same velocity as the driving shaft a^1 . The drum t^2 takes part in the said rotation, the said rotation being not interfered with by the pawl z and the ratchet teeth p .

The pressure of the liquid within the chamber D depends on the load of the driven shaft b , which pressure is transmitted through the passages v^1 and v^2 to the cylinders C^1 and C^2 . If upon an increase of the load of the driven shaft b the pressure of the motive fluid is increased so far that the pressure on the plunger c^2 exceeds the tension of the spring f^2 , the casing l^2 is rocked against the action of the spring f^2 into eccentric position and to the left in Fig. 3, so that the pressure of the fluid is capable to transmit a moment to the drum t^2 . The eccentricity of the drum t^1 within the casing l^1 has the same direction (bearing in mind that in Figs. 2 and 3 the parts are looked at from different directions, as is indicated by the arrows 2 and 3). Therefore the drum t^1 tends to rotate in a direction opposite to the direction of rotation of the driving shaft a^1 . But the said rotation is prevented by the locking mechanism z , p , and the drum t^2 remains stationary. Therefore the pressure of the fluid can act only on the casing g in the direction of the rotation of the shaft a^1 , so that a moment is transmitted to the shaft b which is added to the moment transmitted from t^1 , l^1 . Therefore, the moment transmitted to the driven shaft b is increased in accordance with the moment of the load acting thereon.

If the maximum of the eccentricity between the drum t^2 and its casing l^2 has been attained, and the moment of the load acting on the driven shaft b is not yet completely compensated, the motive fluid acting on the

plunger c^1 reduces the eccentricity of the drum t^1 relatively to its casing l^1 while bending the spring f^1 . Therefore the active vane surface of the drum t^1 is reduced, so that the pressure of the fluid within the chamber 5 D and therefore the moment transmitted to the driven shaft b are further increased without increasing the moment of the driving shaft a^1 .

Upon a reduction of the moment of the load acting on the driven shaft b the pressure within the chamber D is reduced, and the spring f^1 returns the drum t^1 and the casing l^1 into the normal position of highest 15 eccentricity, and thereafter the drum t^2 and its casing l^2 are again set into position concentric to each other. The pressure on the locking mechanism z , p is relieved, and the drum t^2 is again carried along by the casing 20 l^2 in the direction of the rotation of the shaft a^1 by the inner friction of the motive fluid, and there is no relative movement of the inner parts of the gearing.

In the modification shown in Figs. 5 and 6 25 a single intake opening o^6 is made in the cylindrical wall of the pump casing l^5 , and the controlling cylinder C^5 of the said casing is located at the side of the casing diametrically opposite to the point of attachment of 30 the spring f^5 . The springs f^5 and f^6 are in the form of curved springs acting by tension, and they are fixed with one end to the casing g^5 , and at their opposite ends they act on the casings l^5 and l^6 respectively, the spring f^6 35 bearing on a lug q^6 formed on the casing l^6 , and the spring f^5 engaging, with its hook-shaped end f^3 , a nose h^3 of a lever h^5 rockingly mounted on the casing l^5 at h^6 and carrying a weighted body h^7 .

The construction shown in Figs. 5 and 6 40 is important when the load on the driven shaft b is very high, for example when starting the system. While at the beginning of the operation the number of revolutions of the casing g^5 is small, the weighted body h^7 45 is held by the spring f^6 in position adjacent to the casing l^5 . The tension of the spring f^5 is comparatively small, so that the casing l^5 is adapted to be rocked, by the pressure 50 within the cylinder C^5 , from the position of highest eccentricity shown in Fig. 5 towards concentric position. The result of the said displacement is a reduction of the fluid supply 55 and an increase of the pressure thereof during the starting period.

The mass of the weighted body h^7 , and the ratio of the levers of its centre of gravitation and the point where the spring f^5 acts on the lever h^5 relatively to the pivot h^6 are such relatively to the tension of the spring f^5 , that the weighted body h^7 begins to be rocked when the system has attained about one third of the normal velocity. Thereby the spring f^5 is put under higher tension, so that it returns the 65 casing l^5 in opposition to the pressure of the

fluid within the cylinder C^5 into the position of the highest eccentricity.

As appears from Fig. 6, the outlet o^6 of the motor casing l^6 is adapted to be closed, so that in case of direct drive the fluid obstructing action of the motor on the fluid set under pressure by the pump is insured also if the casing of the motor is not exactly symmetrical relatively to the drum. As shown, the casing l^6 is provided with a controlling face 70 s disposed concentrically of the pivot of the casing l^6 , the said face being engaged by lugs n projecting inwardly from the cylindrical wall of the casing g^5 . The said lugs n are disposed and dimensioned so that they are adapted completely to close the two parts of the opening o^6 when the casing l^6 is in median position. The space provided between the said lugs n is open in axial direction, so that the liquid is free to circulate through 80 the said space. By subdividing the opening o^6 into two parts it can be completely laid open by a comparatively small rocking movement of the casing l^6 .

While in describing the invention reference has been made to particular examples embodying the same I wish it to be understood that my invention is not limited to the constructions shown in the drawings, and that various changes may be made in the general arrangement of the apparatus and the construction of its parts without departing from the invention.

I claim:

1. A change speed gearing, comprising a 100 driving member and a driven member, a rotary pump and a rotary motor each comprising a casing, a drum mounted therein and radially movable vanes, said pump and motor being carried by said driven member and having their intakes and outlets connected with each other for causing circulation of a motive fluid from said pump to said motor and from said motor to said pump, the drum of said pump being connected with said driving member, means to lock the drum of said motor against rotation in a direction opposite to the rotation of said driving member, and means controlled by the pressure of the motive fluid for varying the positions of said drums relatively to their casings from 105 concentric positions to eccentric positions, said means being constructed so that the eccentricity of the motor is increased and that of the pump reduced upon an increase of the 110 said pressure.

2. A change speed gearing, comprising a driving member and a driven member, a casing carried by said driven member, a rotary pump and a rotary motor mounted within said casing, a pipe within said casing parallel to the axis thereof, the casings of said pump and motor being rockingly mounted on said pipe and having the outlet of the pump and the intake of the motor commun- 115 120 125 130

cating therewith, the drum of said pump being connected with the driving member and the drum of the motor being capable of rotation only in the direction of the rotation of the driving member, and means acted upon by the pressure of the motive fluid for varying the eccentricity of the motor drum relatively to its casing.

3. A change speed gearing, comprising a driving member and a driven member, a casing carried by said driven member, a rotary pump and a rotary motor mounted within said casing, a pipe within said casing parallel to the axis thereof, the casings of said pump and motor being rockingly mounted on said pipe and having the outlet of the pump and the intake of the motor communicating therewith, the drum of said pump being connected with the driving member and the drum of the motor being capable of rotation only in the direction of the rotation of the driving member, and means operated by the pressure of the motive fluid for varying the eccentricity of said drums relatively to their casings.

4. A change speed gearing, comprising a driving member and a driven member, a casing carried by said driven member, a rotary pump and a rotary motor mounted within said casing, a pipe within said casing parallel to the axis thereof, the casings of said pump and motor being rockingly mounted on said pipe and having the outlet of the pump and intake of the motor communicating therewith, the drum of the pump being connected with the driving member and the drum of the motor being capable of rotation only in the direction of the rotation of the driving member, a spring acting on the casing of said pump and tending to set the pump casing relatively to its drum in a position of high eccentricity, a spring acting on the casing of said motor and tending to set said casing relatively to its drum in centric position, and means acted upon by the pressure of the motive fluid and operative in opposition to said springs for varying the positions of the pump and motor casings relatively to their drums.

5. A change speed gearing, comprising a driving member and a driven member, a rotary pump and a rotary motor carried by said driven member and connected with each other for having a motive fluid circulating from said pump to said motor and from said motor to said pump, the drum of said pump being connected with said driving member and the drum of said motor being capable of rotation only in the direction of the rotation of said driving member, a spring acting on the casing of said pump and tending to set the same relatively to its drum in a position of highest eccentricity, a weighted body rockingly mounted on said pump casing and having a spring acting thereon eccentrically

of its pivot, and means operative by the pressure of the motive fluid and acting in opposition to said spring for varying the eccentricity of said pump casing relatively to its drum.

6. A change speed gearing, comprising a driving member and a driven member, a rotary pump and a rotary motor carried by said driven member and connected with each other for having a motive fluid circulating therethrough, the drum of said pump being connected with said driving member, and the drum of said motor being capable of rotation in one direction only, means controlled by the pressure of the motive fluid for varying the position of said motor drum relatively to its casing from centric position to eccentric position, and means operative in the centric position of said motor drum for closing the outlet of the motor.

7. A change speed gearing, comprising a driving member and a driven member, a casing carried by said driven member, a rotary pump and a rotary motor mounted within said casing, the casing of said motor being rockingly mounted within said casing carried by the driven member for varying the eccentricity of the motor casing relatively to its drum from centric position to eccentric position, the drum of said pump being connected with said driving member, and the drum of said motor being capable of rotation in one direction only, said pump and motor being connected with each other for having a motive fluid circulating therethrough, the outlet of said motor being made in the circumferential wall of the motor casing and ending in a face disposed concentrically on the pivot of said motor casing, a portion projecting from said casing carried by said driven member into position for closing said outlet from the motor when the motor drum is in centric position, and means controlled by the pressure of the motive fluid for varying the eccentricity of said motor casing relatively to its drum.

8. A change speed gearing, comprising a driving member and a driven member, a casing carried by said driven member, a rotary pump and a rotary motor mounted within said casing, the casing of said motor being rockingly mounted within said casing carried by the driven member for varying the eccentricity of the motor casing relatively to its drum from centric position to eccentric position, the drum of said pump being connected with said driving member, and the drum of said motor being capable of rotation in one direction only, said pump and motor being connected with each other for having a motive fluid circulating therethrough, the outlet of said motor being made in the circumferential wall of the motor casing and comprising a plurality of circumferentially spaced sections ending in a face disposed con-

centrically of the pivot of said motor casing, portions projecting from said casing carried by said driven member into position for closing said sectional outlets from the motor when the motor drum is in centric position, and means controlled by the pressure of the motive fluid for varying the eccentricity of said motor casing relatively to its drum.

10. An automatic change speed gearing, comprising a driving shaft and a driven shaft a gear casing connected with said driven shaft, said shafts and casing being coaxially arranged, a rotary pump and a rotary motor enclosed in said casing, the rotor of said pump being connected with said driving shaft, the casings of said pump and motor being suspended within said gear casing for independent rocking movements transverse to the shafts and being hydraulically connected in a closed circuit, and means for producing the said rocking movement by variations in fluid pressure.

10. An automatic change speed gearing, comprising a driving member and a driven member, a rotary pump and a rotary motor each comprising a casing and a piston drum of variable relative eccentricity, means for hydraulically connecting said pump and motor in a closed circuit, means for varying the said eccentricity dependent on the fluid pressure but independent of each other, the piston drum of the pump being connected to the driving member, a gear casing enclosing said pump and motor, said gear casing being connected to the driven member, said pump casing and motor casing being rockingly mounted within said gear casing, and means adapted to hold the drum of said motor against rotation in one direction.

11. An automatic change speed gearing comprising a driving member and a driven member, a gear casing carried by said driven member, a rotary motor and a rotary pump enclosed in said gear casing, the casing of said rotary motor being rockingly mounted within said gear casing, means hydraulically connecting said pump and motor casings in a closed circuit, the drum of said pump being connected with the driving member and the drum of the motor being capable of rotation only in the direction of rotation of the driven member, and means acted upon by the pressure of the motive fluid for varying the eccentricity of the motor drum relatively to its casing.

12. An automatic change speed gearing, comprising a driving member and a driven member, a gear casing carried by said driven member, a rotary pump and a rotary motor enclosed in said gear casing, the casings of said pump and motor being rockingly mounted within said gear casing, and being hydraulically connected in a closed circuit, the drum of said pump being connected with the

driving member and the drum of the motor being capable of rotation only in the direction of rotation of the driven member, and means acted upon by the pressure of the motive fluid for varying the eccentricity of the pump and motor drums relatively to their casings.

In testimony whereof I affix my signature.
